9 Claims. (Cl. 135—3)

Our invention relates to a portable shelter, and more particularly to a portable shelter of improved construction capable of being erected of comparatively great width.

Portable shelters of the prior art generally comprise tents. These tents may be of various sizes but always require tent poles at a plurality of intervals within the shelter, especially if the tent is to be a large one. Then, too, the structural members of the tents of the prior art are awkward to handle and require comparatively large means for transporting the same.

A great many types of portable shelters are coming into demand for military purposes in view of operations in cold climates. Shelters are required not only for housing and messing personnel but also for the storage of equipment and particularly for large aircraft. For this purpose it is imperative that the shelter have an unobstructed floor area.

In our Patent No. 2,511,974, issued June 20, 1950, we have disclosed a hangar tent adapted to house comparatively small aircraft.

One object of our invention is to provide a portable shelter adapted to be disassembled into a comparatively small space and which may be rapidly and expeditiously erected to provide a hangar for a large aircraft.

Another object of our invention is to provide a portable shelter employing multiple roof trusses supported by catenaries.

A further object of our invention is to provide a portable shelter having catenary supported roof trusses in which the catenaries are provided with compression members to resist inward thrust upon the tent poles.

Still another object of our invention is to provide a portable shelter having novel tent poles adapted to resist bending moments.

A further object of our invention is to provide a portable shelter having floating mounting means for the terminal trusses.

A further object of our invention is to provide a novel means for mounting the side curtains of a portable shelter, whereby bending moments due to the weight of the curtains are minimized.

Other and further objects of our invention will appear from the following description.

In the accompanying drawings which form part of the instant specification and in which like reference numerals are used to indicate like parts in the various views:

Figure 1 is a perspective view of a portable shelter with part of the canvas covering broken away showing one embodiment of our invention.

Figure 2 is a fragmentary sectional view taken on the line 2—2 of Figure 1 showing an intermediate roof truss.

Figure 3 is a fragmentary sectional view taken on the line 3—3 of Figure 1 showing an end roof truss.

Figure 4 is a fragmentary sectional view drawn on an enlarged scale taken along the line 4—4 of Figure 1.

Figure 5 is a sectional view drawn on an enlarged scale taken along the line 5—5 of Figure 4.

Figure 6 is a fragmentary sectional view drawn on an enlarged scale showing the method of mounting the end roof trusses on the shelter poles and the manner of mounting the side curtain-supporting cable.

Figure 7 is a fragmentary perspective view drawn on an enlarged scale showing the catenary-compression members, and the mode of mounting the intermediate truss members on the catenaries.

Referring now to the drawings, our portable shelter

2

consists of a framework which may be disassembled and readily transported from place to place. The framework is adapted when erected to be covered by canvas or any other appropriate covering to form the desired shelter.

The framework is supported by four corner tent poles indicated generally by the reference numeral 10. Each of the poles comprises three vertical members 12, 14 and 16 secured in triangular position by a base plate 18, an upper plate 20 and an intermediate plate 22. The vertical members may be formed of tubes of steel or aluminum. The bonding of the vertical tubes by the plates provides a triangular column which is light in weight but is able to resist bending moments. The member 16 extends above the members 12 and 14, and the front catenary, indicated generally by the reference numeral 24, is secured between the two members 16 of the left front and right front corner columns. Similarly, the rear catenary member, indicated generally by the reference numeral 26, is secured between the members 16 of the left rear and right rear corner columns. To the members 16 we secure the guy ropes 28 and 30, there being one pair for each corner column. The guy ropes 28 are in the same plane as the catenary member 26 at the rear and the catenary member 24 at the front. The guy ropes 30 lie in a plane generally normal to the plane in which the guy ropes 28 lie. The ends of the guy ropes are secured to the ground by suitable stakes 32. The guy ropes may be provided with appropriate turn buckles 34 adapted to adjust the tension upon individual guy ropes.

Across the front of the tent the catenary which is indicated generally by the reference numeral 24 is shown in greater detail in Figure 7, to which reference is now had. It comprises a wire cable 34 which is anchored in any apt manner to the members 16 of the front corner columns. The wire 34 carries a shoe 36 which forms the end of a demountable crescent truss such as shown in our copending application Serial No. 213,246, filed February 28, 1951. The truss comprises a plurality of rigid tubular members 38 adapted to interfit to form an elongated curved rigid truss member indicated generally in Figure 1 by the reference numeral 40. A pair of flexible members 42 and 44 extend from end to end of the rigid truss member. The flexible members are held in spaced position by a plurality of spreader members 46. The spreader members are secured to the rigid truss member 40 by tie members 48 which tie the spreader members 46 to the curved rigid truss member. The truss member, of course, is formed in sections so that it can be readily demounted.

Referring again to Figure 7, the catenary wire 34 extends through a plurality of tubes 50. As can be seen by reference to Figure 1, the right-hand tube 50 extends between the right-hand corner column member 16 and the shoe 36 of the right-hand intermediate truss. The intermediate member 50 extends between the shoe 36 of the right-hand intermediate truss and the shoe 36 of the left-hand intermediate truss. A third tubular member 50 extends between the left-hand member 16 of the front corner column and the left front truss shoe 36. In a similar manner, the rear catenary member 36 is formed of a catenary wire which carries the shoe of the rear ends of the intermediate trusses and the tubular compression members 50 similarly positioned in the rear as in the front. The intermediate crescent trusses are thus supported by a pair of catenary flexible members which conveniently may be wire cables. It is to be understood, of course, that they may be made of nylon or any other flexible material sufficiently strong to carry the load. The use of the compression members 50 around the catenary cables transfers a portion of the load to the compression members and thus relieves the corner columns of part of the bending moment occasioned by the thrust upon the catenary. It will be readily appreciated that but for the compression members the load transmitted to the catenary cables by the trusses would tend to draw the upper portions of the corner columns toward each other. This load, of course, would have to be taken by the guys 28. In order to lessen the load upon the guys we employ the compression members mounted about the catenary cable. It will be observed by reference to Figure 7 that we provide a plurality of positioning means 52 to maintain the catenary cable 34 coaxial with the

80

tubular members 50. It is of advantage to reduce the load upon the stakes. It is not known in advance the character of terrain in which our portable shelter is to be erected. A stake must be designed for average conditions and should have a sufficient factor of safety. In some terrains the holding power of the soil may be low. Then, too, rain may frequently reduce the holding power of the surrounding soil. For wind and snow loads sudden stresses may be encountered and if the entire load were taken by the stakes, failures are apt to be encountered. Our use of compression members in conjunction with the catenary prevent excessive loads from being placed suddenly upon the tent column or pole guy rope stakes. The positioning means 52 may advantageously take the form of disks 52 fitted in the tubular compression members 50. The disks are provided with openings for the passage of the catenary cable 34. It is the purpose of disks 52, which position cable 34 within tube 50 at intervals, to reduce the slenderness ratio from that of the predetermined column length between the abutting ends of each tube to shorten the length intermediately unsupported. The degree of support given by each disk 52 increases in proportion to the tension exerted or applied to the catenary wire 34. It is clear that as increased tension is applied to catenary wire 34, its rigidity increases in the arrangement described. This rigidity, in consideration of the tensile strength of cable 34, permits of a light wall tubular compression member that would normally be too weak to support the degree of compression to which the total length of tubes 50 are subjected.

The end or side crescent arch trusses, indicated generally by the reference numeral 54, are of a different construction in that only one flexible member 56 is used instead of two. The spreader members are not employed. The rigid arcuate member 58 is sectional and when assembled spans the shelter from front to back, as can readily be seen by reference to Figure 1. The flexible member 56 is tied to the rigid member 58 by means of tie members 60. The lateral or end arches are made in this manner in order that a flush surface may be presented for the end curtain 62. A plurality of purlins 64 extend between trusses, as can readily be seen by reference to Figures 1 and 4. Any appropriate means for securing the purlins to the trusses can be employed. As can be seen by reference to Figure 4, the rigid member of the intermediate truss carries a transverse member 66 and the rigid member 58 of the end truss 54 carries a member 68. The purlin 64 is secured between members 66 and 68 by means of bolts 70 and 72. The purlins may be made of aluminum or plastic and may advantageously have a T-shaped cross section, as shown in Figure 5, with a tapering web 74.

In its broadest aspect our framework comprises four corner columns between which extend catenary cables. These catenary cables carry intermediate crescent arches spaced from each other by appropriate distances. The columns themselves carry the end crescent arches. These crescent arches may be considered as costal members or costal trusses. The purlins 64 extend at right angles to the costal members and are intercostal members. The roof is therefore formed by a plurality of costal trusses the end trusses of which are supported by the columns and the intermediate trusses of which are supported by catenary cables carried by the corner columns. These trusses are tied together intermediate their ends by a plurality of intercostal members.

It will be observed that the intermediate trusses are supported by catenary cables while the end trusses 54 are supported from the members 12 of the corner columns. Since the support of the intermediate trusses through the catenaries is flexible, we provide a floating means for supporting the end trusses. This can readily be seen by reference to Figure 6. The tubular rigid member 58 of the end truss is supported by a shoe 76 which rests upon the top of the tubular member 12 of the corner column, there being one shoe for each end. The top of the tubular member carries a threaded plug 78 provided with a slot 80. The top member 82 of the column is likewise formed with a slot 84. Through these slots we position a bolt 86 which slidably secures the end of the shoe 76 to the top of the column. It will be observed that the column is free to move inwardly with respect to the truss shoe a limited distance. The shoe carries a depending portion 88 which in turn carries a pivot pin 90 around which is pivoted a lever 92 intermediate its ends.

The bottom portion of the lever 92 is formed with a projection 94 which abuts the post 12. To the upper arm 96 of the lever we attach the curtain wire 98. It will be readily understood that the weight of the curtain upon the curtain wire will tend to rotate the lever 92 in a clockwise direction, thus thrusting the upper portion of the column outwardly. If the curtain wire were supported directly from the post 12 the weight of the curtain would tend to pull the top of the post 12 inwardly. The weight of the curtain is, of course, carried by the shoe 76 through the depending portion 88. It will also be observed that as the truss 54 deflects under a load the ends of the truss are free to move outwardly. This outward movement would tend to taunt the curtain wire 98 and in turn to rotate the lever 92. The applied force of the curtain rod is caused to react upon the pole 12 in an equal and opposite direction and the shoes 76 are free to move as the end truss deflects under the load. The front and back curtains of the tent are carried by transverse curtain wires 100, as can readily be seen by reference to Figure 1. In order to transmit torsional stresses upon the roof to the corner columns we provide diagonal tension wires 102, 104, 106 and 108. Wire 102 extends from the center of intermediate truss 40 to the front right corner column. Wire 104 extends diagonally from the center of intermediate truss 40 to the right-hand rear corner column. In a symmetrical manner wires 106 and 108 extend from their respective corner columns to the center of the left-hand intermediate truss.

The structure shown in Figure 1 is fifty feet deep, twenty-one feet high and sixty feet wide. It will be seen that we have provided an unobstructed floor area of three thousand square feet. Our shelter could remain portable even though it were constructed of a depth of one hundred fifty feet, that is, if the length of the trusses were one hundred fifty feet. We have found that in our construction a truss in excess of this length cannot practically be made and remain readily portable.

In use, let us assume that the crescent trusses have been disassembled and that all parts are in conveniently portable packages. The dimensions of the shelter are known. A site is chosen and the four corner columns erected. The guy ropes are then placed in position and secured to stakes which have been driven into the ground at the appropriate positions determined by the position of the corner columns. The front and rear catenary cables are then strung and the lateral or end trusses are then placed in position. The intermediate arches are then placed in position, it being understood, of course, that the shoes for these arches are already in position on the front and rear catenary wires. The center intercostal members or purlins may then be placed in position and the diagonal cables 102, 104, 106 and 108 placed in position. The remaining purlins, or intercostal members, are then secured between the trusses. The side curtain wires may advantageously be placed in position at this time, thus completing the erection of the framework. Preferably the curtain wires are mounted on all four poles and the guy lines are adjustably secured to the poles prior to mounting the crescent trusses. The roof-covering 110 is then positioned over the roof. This covering may advantageously be provided with tying tapes (not shown) secured to the roof-covering for tying around the purlins at predetermined positions. The side curtains are then draped over the side curtain wires and the rear curtain placed in position over the rear curtain wire. The front curtain may be equipped with means for rolling it (not shown) as is well understood in the art. It is further to be understood that any of the side curtains may be provided with entry flaps to admit personnel. It will be seen that our shelter is quite strong and adapted to resist wind and snow loads. All of the members are adapted to flex under applied stresses. An elongation of the intermediate trusses due to snow loads, for example, is readily accommodated for by the flexible suspension of these members by the catenary cables. The floating positioning of the end shoes of the outboard trusses permits a flexing of these members. The compression members 50 limit the moments applied to the top of the corner columns by the catenaries. The entire structure, therefore, is flexible, though sufficiently rigid to retain its shape and perform its function. The flexibility of the structure prevents failures even though our shelter may be subjected to sudden large forces due to high or gusty winds. Since the areas involved are great it will be readily appreciated that the wind load is

large. In addition, the load upon the roof under heavy snow would be great. A heavy roof load would also be imposed by ice which forms on the roof during certain conditions such as freezing rain followed by low temperatures.

It will be seen that we have accomplished the objects of our invention. We have provided a portable shelter adapted to be disassembled into a comparatively small space for rapid and expeditious erection to provide a hangar for a large aircraft. We have provided a portable shelter employing multiple roof trusses the intermediate ones of which are supported by catenaries. We have provided catenaries for supporting roof trusses equipped with compression members for resisting inward thrust upon the tent poles. We have provided a shelter having improved tent poles adapted to resist bending moments. Our shelter has end trusses provided with floating mounting means for suspending the side curtains.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is therefore to be understood that our invention is not to be limited to the specific details shown and described.

Having thus described our invention, what we claim is:

1. In a shelter a pair of front columns, a pair of rear columns, a catenary cable carried by and extending across the front columns, a catenary cable carried by and extending across the rear columns, an intermediate roof truss supported by the catenary cables, a pair of outboard roof trusses supported by and extending between the respective front and rear columns and a covering carried by the roof trusses.

2. In a shelter a pair of front columns, a pair of rear columns, a catenary cable carried by and extending across the front columns, a catenary cable carried by and extending across the rear columns, a readily demountable intermediate roof truss supported by the catenary cables, a pair of readily demountable outboard roof trusses supported by and extending between the respective front and rear columns and a covering carried by the roof trusses.

3. In a shelter a pair of front columns, a pair of rear columns, a catenary cable carried by and extending across the front columns, a catenary cable carried by and extending across the rear columns, a pair of readily demountable intermediate roof trusses supported by the catenary cables, a pair of readily demountable outboard roof trusses supported by and extending between the respective front and rear columns and a covering carried by the roof trusses.

4. In a shelter a pair of front columns, a pair of rear columns, a catenary cable carried by and extending across the front columns, a catenary cable carried by and extending across the rear columns, a pair of readily demountable intermediate roof trusses supported by the catenary cables, a pair of readily demountable outboard roof trusses supported by and extending between the respective front and rear columns, a tension member extending substantially from the center of one of the intermediate roof trusses to one of the front columns, a tension member extending from said intermediate point to the

corresponding rear column, a tension member extending from substantially the center of the other of the intermediate roof trusses to the other front column, a tension member extending from said last named point to the corresponding other rear column and a covering carried by the roof trusses.

5. In a shelter a pair of front columns, a pair of rear columns, a catenary cable carried by and extending across the front columns, a catenary cable carried by and extending across the rear columns, a truss shoe carried by the front catenary cable, a truss shoe carried by the rear catenary cable, an intermediate roof truss supported by the shoes, tubular compression members mounted upon the catenary cables and extending from the intermediate truss shoes to the columns, the construction being such that the tendency of the columns to deflect inwardly under the weight upon the roof truss will be resisted by the compression members.

6. A shelter as in claim 5 in which said tubular compression members are fitted with positioning means carried therewithin, said positioning means being formed with openings, said catenary cable passing through said openings, the construction being such that said positioning means will maintain the catenary cable substantially coaxial with the tubular compression members.

7. In a shelter a pair of front columns, a pair of rear columns, a catenary cable carried by and extending across the front columns, a catenary cable carried by and extending across the rear columns, an intermediate roof truss carried by the catenary cables, each of said columns comprising three vertical members positioned at the apices of a triangle and means for maintaining the vertical members in said triangular relationship.

8. In a shelter a pair of columns, a pair of shoes, means for floatingly securing said shoes to the tops of said columns for movement transverse to the column axes, a truss supported by said shoes and a pair of levers, means for pivoting the levers to respective shoes intermediate their ends, each of said levers being provided with a lug contacting the respective tent columns and projecting from the lower portions of the levers and a curtain supporting wire having its ends secured to the levers at their respective opposite ends.

9. In a shelter a roof comprising a plurality of costal trusses, a plurality of intercostal members extending between trusses, a pair of front columns, a pair of rear columns, catenary cables extending across the front columns, catenary cables extending across the rear columns, means for mounting the roof with its intermediate trusses supported by the catenary cables and with its outboard trusses mounted upon said columns and a covering carried by the roof.
